KNOCKDOWN CONTAINER

Glynn Artnie Britton, Washington, D. C.

Application February 1, 1943, Serial No. 474,331

4 Claims. (Cl. 217—12)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to improvements in containers or boxes of the collapsible knockdown type and the main objects of the improvements are:

First, to provide a strong, convenient, and inexpensive packing case or box that can be readily and easily taken apart for access to the contents thereof or for return shipment in a flat, knocked-down condition.

Second, to permit the use of lighter materials in the construction of the box with a minimum requirement of metal or similar critical substance and without sacrificing sturdiness or durability of structure.

Third, to provide a construction in which the more critical structural elements, such as metal corner brackets, are specially sheltered and protected from damage or injury in the knocked-down condition of the box as well as in the assembled or loaded condition of the latter; such construction permitting prolonged use of corner brackets of lighter gauge metal.

Fourth, to provide a construction whereby the joints of the box are sealed and made impervious to moisture automatically and coincidentally with the fastening in place of the top, bottom and side members of the box.

Fifth, to provide a knockdown box structure in which the elements forming the enclosing walls of the box preferably though not necessarily are similar in construction and design whereby they can be used interchangeably to form the top, bottom and sides of the box, and

Sixth, to provide a special and novel type of corner bracket and locking key for connecting the various box-forming members at adjacent edges, and adapted to be readily stamped or otherwise formed of spring steel or cheaper metal.

With the above objects in view, the invention resides in the novel construction, arrangement, and combination of parts hereinafter more fully described and pointed out with reference to the accompanying drawings wherein:

Figure 1 is a perspective view of a box formed of members constructed and fully assembled according to the invention;

Figure 2 is a similar view of the box with one of the members displaced;

Figure 3 is a vertical section on line 3—3 of Figure 1;

Figure 4 is a vertical section on line 4—4 of Figure 1;

Figure 5 is a perspective view of the box-forming members in knocked-down and stacked condition;

Figure 6 is an exploded view of one of the corner fasteners showing the component parts thereof in perspective;

Figure 7 is a view in perspective of a fragment of a corner bracket showing a modification in the construction thereof.

In the depicted embodiment of the invention, the box comprises a top member A, bottom member B and four side members C, D, E, and F. These members are identical in construction and design and hence may be used interchangeably to enclose the top, bottom and sides of the box. Each member comprises a body or panel of plywood or other desired material suitable for the intended purpose and use of the box; the member being rectangular with adjacent sides unequal and opposite sides equal in length. Re-entrant angles or recesses are provided in the shorter sides of each panel at the corners of the panel, one side or edge surface 1 of each recess being perpendicular to the edge surface 2 of the adjacent shorter side of the panel and the other side or edge surface 3 of the recess being perpendicular to the edge surface 4 of the adjacent longer side of the panel. The maximum depth of the recess, measured along the surface 1 from the edge 2 of the panel to the vertex 5 of the angle does not exceed the thickness of the panel. The maximum length of the recess, measured along the surface 3 from the edge 4 of the panel to the vertex 5 of the angle is greater than the thickness of the panel in a ratio of 5 to 1, approximately.

The box-forming members are respectively provided at each corner with two metal brackets G and H. Bracket G comprises a thin rectangular sheet of spring metal having longitudinal slots or cut-outs forming a pair of laterally spaced strips 6 of appropriate length extending between and connected to non-slotted portions at each end of the sheet which serve as attaching plates 7 and 8. Bracket H comprises a similar sheet of metal also slotted longitudinally to provide three laterally spaced strips 9 extending between and connected to attaching plates 10 and 11. These brackets may be cut out, stamped or otherwise formed individually in one piece from suitable metal, preferably spring steel, and in final form are substantially U-shaped as shown in Fig. 6 with the attaching plates disposed in spaced parallel planes and the strips bent to form sub-

stantially V-shaped loops inverted over and bridging the space between the plates on one side thereof. One portion or leg of each loop of a bracket is disposed in the plane of one of the attaching plates of the bracket (i. e. plates 7 and 11) to form a straight-line extension thereof and the other portion of the loop is inclined to the planes of the attaching plates to provide a sloping surface extending obliquely from its junction with the other attaching plate of the bracket (i. e. plates 8 and 10) to the outer end of the other and straight portion of the loop.

Brackets G straddle the panel across the recesses in the shorter side of the panel with the outer ends of the bracket loops 6 flush with the adjacent edge surfaces 2 of the panel. Brackets H are arranged at right angles to their companion brackets G and straddle the longer sides of the panel with the bracket loops 9 extending outwardly over the adjacent edge surfaces 4 of the panel a distance approximately equal to the depth of the recesses or the height of the loops 6. The paired brackets G and H are mounted on the common panel so that the straight portions of the loops are all on the same face of the panel and the spacing between the loops of the various brackets is uniform so that the loops 6 of the brackets G of one panel may be accommodated in the spaces between the loops 9 of the brackets H on the other panels. The brackets are shown securely attached to their respective panels by fasteners 12, such as rivets; bolts, etc., connecting the attaching plates through the material of the panel. In lieu of fasteners 12 or as supplementary thereto, pointed projections or prongs 13, such as shown in Figure 7, may be formed or made integral with each attaching plate and pressed into the panel to fasten the bracket in place. The paired brackets G and H of each panel are set back slightly from the corners of the panel as shown at 14.

In the assembled or box-forming condition of the panels, the latter are arranged as shown in the drawings with the straight portions of the bracket loops on the inside of the box. Also, each panel has its shorter edges 2 overlapping the longer edges 4 of two parallel panels adjacent thereto and its longer edges overlapped by the shorter edges of two other parallel panels adjoining therewith. By this arrangement the panels mutually support and reinforce one another to provide a sturdy structure while at the same time providing for the interconnection of the brackets within the angles or recesses at the corners of the box, as shown in Figures 1 and 2. It will be observed that in the setup condition of the box, three pairs of interconnected brackets appear adjacent each corner of the box and that they are disposed about axes mutually perpendicular and converging at the corner of the box. Since the inclined or oblique portions only of the loops are exposed at the edges of the box and since these portions are set back from the corners and solid edges of the box, no contact occurs between the bracket loops and the ground or floor on which the box is supported, whether the latter is at rest, sliding, or turned end over end about any edge or corner thereof. Hence, the weight or load of the box is sustained solely by the corners 14 or by the solid edges 2 of the box. Because of their shielded positions, the metal brackets can be made of lighter material than is required for brackets exposed to blows and knocks incident to the shifting and transporting of loaded containers. The sloping sur-

faces presented by the bracket loops are of advantage, also, in protecting the loops against damage or injury from protruding nails in floors of trucks, cars, warehouses, etc. or from loose objects thereon and over which the box is inadvertently rolled or slid. Upon encountering such objects, the loops by reason of their obliquity will readily slide or pass over same without tendency to snag thereon.

The interconnection of brackets G with brackets H is accomplished by the use of split tubular keys 15 of triangular contour conforming to the contour of the opening or passage through the loops of interengaged brackets. Each key is preferably formed of a rectangular sheet of spring steel bent into triangular shape with the free ends 16 of the sheet bent inwardly of the key and in spaced relation along the middle of one side of the key to provide the slot 17. By reason of the slot, the key can be expanded and contracted in size and the inturned ends 16 serve as stop flanges limiting the contraction of the key. The length of the key is preferably such that when the key is inserted in the loops, only a slight portion thereof is exposed at the outer end of the loops, sufficient to be grasped by pliers or other means for extracting the key. The key is normally oversized to the extent of requiring slight compression prior to insertion in the bracket loops and as it expands within the loops exerts a pressure against the loops which strengthens and reinforces the latter as well as serving to frictionally hold the key in place.

Since the keys are not extended so as to fill out the corners of the box or container, the weight of the loaded container does not fall on the exposed ends of the keys when the container is turned end for end or rolled over from corner to corner as is often practiced in shifting the container from one location to another. During such movement of the container, the weight strikes directly on the edges 14 of the container at a common meeting place or corner. This construction is advantageous not only in regards to affording protection to the keys and prolonging the usefulness of the same but also in respect to the amount of critical material required in their construction since the keys, as well as the brackets, can be made of a lighter guage of metal than would otherwise suffice. As a safeguard against loss, the keys may be pinned or wired to the loops of a bracket. To this end, certain loops of given brackets, such as the end loops of brackets H, are apertured as shown at 18 and a similar aperture 19 is provided in a side of key 15 near one end thereof. When the key is properly positioned within the loops of a bracket H, in either the setup or knockdown condition of the panels, the aperture 19 in the key registers with one of the apertures 18 in the bracket and a cotter-pin 20 is inserted in the registering apertures and clinched to hold the key in place. In lieu of a cotter-pin, a wire-seal may be used to secure the key.

In order that the joints of the box or container may be sealed and made impervious to moisture as far as practicable, each panel is provided with two ribs or strips of moulding 21 on its inner face and in parallelism with and respectively adjacent the longer sides or edges 4 of the panel. Each rib serves as a seat or support for packing or sealing elements and presents a flat face or side perpendicular to the inner face of the panel and substantially flush with the adjoining edge 4 of

the panel. Seated in a longitudinal groove or channel in the flat face of each rib is a sealing or packing element 22 of suitable composition, such as a rope of asphalt, oakum, or wax-treated material. These sealing elements preferably are circular in cross section and extend slightly beyond the longer sides of the panels so that in the setup condition of the panels, the elements of each panel are engaged by the adjacent shorter sides 2 of adjoining panels as will be understood from Figures 3 and 4 of the accompanying drawings. When the panels of the container are drawn together by the insertion of the keys 15 in the corner brackets, the various sealing elements are thereby automatically compressed and flattened between their respective seating channels and the adjacent confronting portions of the adjoining panels. Hence they serve to seal the box along the sides or joints and prevent moisture from reaching the contents of the box from the outside thereof.

From the foregoing it will be seen that the invention provides for simplification in the construction of collapsible containers, the use of lighter material in the construction of same, special protection for the more critical material which is metal, and for excluding moisture at the joints of the container. A box or container constructed and designed as herein described is well adapted for use as a shipping container for light or heavy articles and for many other purposes.

Having thus described the invention, I claim:

1. A knockdown container comprising identical rectangular wall-forming members respectively of greater length than width and provided with reentrant recesses in the shorter sides thereof at the corners, said members being relatively arranged in box-formation with the shorter sides of each member overlapping adjacent longer sides of two adjoining members to provide at each corner of the container three mutually perpendicular reentrant recesses, angle loops secured to the said members in set-back relation to the corners of the members, the loops of each member interfitting with the loops on the adjoining members across the intervening recesses, said loops having flat surfaces extending obliquely of the recesses and split tubular pins extending through and expanded within interfitting loops with slight portions only of the pins exposed at the outer ends of the loops.

2. A knockdown container comprising identical top, bottom, side and end members each of which is rectangular with its adjacent sides unequal and its shorter sides provided with reentrant recesses at the corners, said members being arranged in box-formation with the shorter sides of each member overlapping adjacent longer sides of two adjoining members and providing three mutually perpendicular reentrant recesses adjacent and converging at each corner of the container and solid portions forming the edges of the container between the recessed corners of the latter, and separable fastening means be-

tween and connecting adjoining members across the intervening corner recesses in set back relation to the corners and the said solid edge portions of the containers whereby when the container is turned end over end or about any edge thereof the weight or load of the container is sustained solely by the solid edges of the container and the fastening means shielded against damage or injury.

3. In a knockdown container, the combination of identical rectangular wall-forming members individually of greater length than width and collectively arranged in box-formation with the shorter sides of each member overlapping adjacent longer sides of two adjoining members, each member having corner recesses in its shorter sides exposing edge portions of the adjacent longer sides of the adjoining members and forming therewith reentrant angles in the corner edges of the container, loops secured to each member at the shorter sides thereof in setback relation to the corners and disposed within the corner recesses, other loops on each member projecting beyond the longer sides thereof in setback relation to the corners of the member, said other loops being complementary to and interfitting with the loops in the adjacent corner recesses of adjoining members, said loops being triangular in cross-section and extending obliquely across the reentrant angles in the container, and normally oversized split tubular keys of elastic material and triangular contour extending within and tensionally connecting interengaged loops of the member, said keys being in setback relation to the solid edges at the corners of the container.

4. In a knockdown container structure, a wall-forming unit comprising a rectangular panel of greater length than width and having corner recesses similarly of a depth greater in the width direction of the panel than the thickness of the latter but in the lengthwise direction of the panel not in excess of such thickness, and laterally spaced loops of uniform width and triangular cross-section at each corner of the panel and arranged in two separate groups extending outwardly of the edges of the panel on opposite sides respectively of and in setback relation to the intervening corner of the panel with the loops on the longer side of the panel located within a maximum distance from said corner not exceeding the maximum depth of the corner recess and the loops on the shorter side of the panel disposed within the corner recess and setback from the corner a distance exceeding by the width of a loop the setback distance of the companion loops on the longer side of the panel, each loop having a straight portion substantially in the plane of the inner face of the panel and extending forwardly of the adjacent edge thereof a distance not exceeding the minimum depth of a corner recess and having an inclined portion extending across the edge of the panel obliquely between the outer face of the panel and the upper end of the said straight portion.

GLYNN ARTNIE BRITTON.
